UNITED STATES PATENT OFFICE

HAROLD P. BROWN, OF MONTCLAIR, NEW JERSEY.

ELECTRIC BOND FOR RAILWAY-RAILS.

SPECIFICATION forming part of Letters Patent No. 657,757, dated September 11, 1900.

Application filed February 18, 1899. Serial No. 705,950. (No model.)

To all whom it may concern:

Be it known that I, HAROLD P. BROWN, a citizen of the United States, and a resident of Montclair, in the county of Essex and State 5 of New Jersey, have invented a new and useful Electric Bond for Railway-Rails, of which the following is a specification.

My invention relates to an electric bond for railway-rails in which fixed plugs of suitable 10 electric conducting material have their ends immersed in or engaged with bodies of plastic alloy, which is a plastic-metal compound having high electrical conductivity. These ends are free to change their positions within pre- 15 determined limits within the bodies of plastic alloy to accommodate the movement of the ends of the rails.

A practical embodiment of my invention is represented in the accompanying drawings, 20 in which—

Figure 1 is a vertical transverse section through a railway-rail and one of the electric bonds, showing the parts in the position which they occupy when in use. Fig. 2 is a view 25 in side elevation, partly in section, of the meeting ends of two rails with the bond in position, the section being taken in the plane of the line 2 2 of Fig. 1. Fig. 3 is a top plan view of a bond-plate. Fig. 4 is a transverse 30 section of a rail and angle-plate, showing a modified form of the bond; and Fig. 5 shows a modified form of bond-plate.

Referring to the form shown in Figs. 1 to 3, inclusive, A represents the base of one rail 35 and A' the base of the adjacent rail. Through the flanges of said bases holes a and a' are bored at distances of two inches (more or less) from the ends of the rails, the said holes having, preferably, a slant, as shown, to carry 40 the boring-tool clear of the head of the rail.

In the holes a a' plugs B B', of copper or other suitable electric conducting material, are firmly set, with their outer ends flush with or they might be below the upper surfaces of 45 the bases A A' and their lower ends projecting below the lower faces of the said bases A A'.

To insure a perfect electrical connection between the plugs B B' and the walls of the holes in which they are fixed and to prevent 50 corrosion of the contact-surface, the walls of the holes and the exterior surfaces of the

plugs are first amalgamated by applying, for example, what is now known in the art as the "Edison solid alloy." This is an easily-decomposed alloy of mercury, which will amalgamate the surface and permanently protect it from rust, as the mercury will penetrate some distance into the metal and resist any tendency to oxidize. A groove b is provided longitudinally along the surface of the plug, 55 for reasons which will hereinafter be stated. A bond-plate C, preferably of flat form, as shown, is adapted to rest on the railway-tie beneath the meeting ends of the rails and has a width sufficient to extend back from 60 the meeting ends of the rails to a point beyond the projecting ends of the plugs B B'. The plate C is provided with cups c c', formed in its upper face at points which will register with the projecting ends of the plugs B B'. 65 The cups c c' have a horizontal diameter greater than the diameter of the plugs which project into them, leaving a free play for the plugs in every direction to an extent equal to or greater than any displacement of the rails, 70 which is liable to occur either under the influence of the temperature or traffic. The projecting ends of the plugs preferably terminate a short distance above the bottoms of the cups when the parts are assembled. After 75 the walls of the cups c c' have been amalgamated the cups are filled with a plastic alloy which adheres to the amalgamated surfaces of the cups and plugs and adapts itself to the movements of the plugs, thereby keeping 80 the contact perfect under all conditions, and produces a path of very low resistance from rail to bond-plate and from bond-plate to rail. Whenever the plugs are suddenly jarred or forced downwardly into the cups, 85 the plastic alloy is permitted instant relief by passing up the grooves b on the plugs. These grooves also furnish relief for the body of plastic alloy under changes of temperature. The forcing of the plastic alloy up the grooves 90 b serves also to maintain a perfect electrical 95 contact between rail and copper plug.

The bond-plate C has openings for receiving the spikes which hold the rail in position. In the present instance four of these openings are provided (denoted by D D' D² D³) and arranged in staggered order relatively to the 100

longitudinal axis of the rail, so that at least two of the openings—one on each side of the base of the rail—will be in position to receive the spike, whatever be the width of the rail-base, within the limits of the rails at present in common use.

When the parts are in assembled adjustment, the angle-plate E covers the plugs B B' and effectually prevents them from working out should there be any such tendency.

In the modified form shown in Fig. 4 the angle-plate C' is used as a bond-plate, and the plugs B² are fixed in it, while the cups c² for receiving the plastic alloy are formed in the base-flange of the rail. This amounts to essentially a reversal of the arrangement shown in Figs. 1, 2, and 3, where the plugs are fixed in the rail and cups formed in the bond-plate instead of cups formed in the rail and plugs fixed in bond-plate. This modified structure is of especial importance in bonding rails which have been laid for a greater or less extent of time, as it does not require the removal of the angle-plates, and hence the work of bonding does not interfere in the least with traffic. In this instance I find it desirable to bore with a drill having a very obtuse point, thereby carrying down a bur from the lower edge of the angle-plate into the base of the rail to close the joint between the base and plate, and to further seal said joint after the walls are amalgamated I force an amalgamated copper tube F into the hole, and then after putting in the charge of plastic alloy the "T-plug" B² is forced in, its head being locked to the plate C' and its body free to move in the plastic mass, the copper tube yielding the necessary amount.

In both of the forms shown gravity is utilized to hold the plastic material in place, however loose the joints may become.

Should the plate C be insufficient to satisfactorily carry the current, its conductivity may be increased by connecting the cups c c' by a rod of copper or other metal of high conductivity, the plate C² being provided with a channel c³ to receive such connecting-rod, as shown in Fig. 5.

It is evident that either form of this invention may be used to electrically connect contiguous sections of metal pipes, wires, cables, bars, or other conductors, and that changes might be resorted to in the form and arrangement of the several parts without departing from the spirit and scope of my invention. Hence I do not wish to limit myself strictly to the structure herein shown and described; but

What I claim is—

60 1. The combination with adjacent rails, of a bond-plate arranged to overlap the meeting ends of the rails, the bond-plate and the rails being provided, the one with electric conducting-plugs fixed thereto and the other with bodies of plastic alloy in position to permanently engage the said plugs, substantially as set forth.

2. The combination with the adjacent rails, of a plate arranged to overlap the meeting ends of the rails and extended along the flanges at the bases of the rails, the said plate and the flanges at the bases of the rails being provided, the one with electric conducting-plugs fixed thereto and the other with bodies of plastic alloy arranged to permanently engage the said plugs, substantially as set forth. 75

3. An electric bond comprising a plate provided with cups for holding bodies of plastic alloy and rails provided with electric conducting-plugs fixed in their base-flanges with their free ends projecting below the base-flanges in position to enter the bodies of plastic alloy, substantially as set forth. 80

4. An electric bond comprising a bond-plate arranged to receive thereon the meeting ends of railway-rails and provided with cups for receiving bodies of plastic alloy and rails provided with electric conducting-plugs fixed in their flanges and projecting therefrom in position to dip into the bodies of plastic alloy, 90 the said plug being located in position to be covered by the usual angle-plate, substantially as set forth. 85

5. In combination a bond-plate adapted to receive the meeting ends of adjacent railway-rails and provided with cups for receiving bodies of plastic alloy and rails having electric conducting-plugs fixed in their base-flanges and projecting therefrom into the bodies of plastic alloy, the said plugs and the wall of the opening in which they are fixed being spaced from one another throughout a small extent of the periphery of the plug to form relief-conduits between the body of plastic alloy and the top of the base-flange 105 of the rail, substantially as set forth. 95

6. The combination with the base-flanges of the rails provided with holes extending therethrough, of electric conducting-plugs fixed in said holes and projecting below the rail-bases and means for maintaining bodies of plastic alloy in permanent engagement with the ends of said plugs, substantially as set forth. 110

7. The combination with rail-bases having electric conducting-plugs fixed therein and projecting below the bottoms of the rail-bases, of a bond-plate provided with cups in position to receive the projecting ends of said plugs and bodies of plastic alloy in said cups 115 in engagement with the plugs, the projecting ends of the plugs being normally spaced from the walls of the said cups, substantially as set forth. 120

8. The combination with rail-bases provided with perforations therethrough, the walls of said perforations being amalgamated, of amalgamated electric conducting-plugs fixed in said holes in the bases and a bond-plate provided with bodies of plastic alloy 130 in position to permanently engage the said plugs, substantially as set forth. 125

9. In an electric bond, the combination of two or more contiguous conductors, a recep-

tacle formed in one conductor containing a plastic-metal compound and a plug or rod electrically connected to a second conductor and dipping into the said plastic-metal compound, the said plug or rod having a free limited movement relatively to the said first-named conductor, substantially as set forth.

10. In an electric bond, the combination of two meeting conductors, a hole formed in one conductor containing a plastic-metal compound, and a plug, rod or projection electrically connected to a second conductor and dipping into the said plastic-metal compound, the contact-surfaces of said plugs and holes 15 being amalgamated or rubbed and impregnated with a decomposable alloy of mercury, substantially as set forth.

11. In an electric bond, the combination of two meeting conductors, a receptacle formed 20 in one conductor, a plastic-metal compound in said receptacle, a projection from the second conductor dipping into the said receptacle and means for clamping or binding the two conductors together, the said projection 25 having a free limited movement relatively to

the said first-named conductor, substantially as set forth.

12. In an electric bond, the combination of two meeting conductors, plugs or projections extending from same into holes in a third overlapping conductor and a plastic-metal compound contained in said holes, substantially as set forth. 30

13. In an electric bond, the combination of two meeting conductors, plugs or projections 35 extending from same into holes in a third overlapping conductor, a plastic-metal compound contained in said holes and an adherent coating of amalgam on the contact-surfaces of said plugs and holes, substantially 40 as set forth.

In testimony that I claim the foregoing as my invention I have signed my name, in presence of two witnesses, this 9th day of February, 1899.

HAROLD P. BROWN.
